UNITED STATES PATENT OFFICE.

WILLIAM ZURICH, OF PRINCETON, NEW JERSEY.

FRAMING-TOOL.

1,178,985.

Specification of Letters Patent. Patented Apr. 11, 1916.

Application filed October 2, 1914. Serial No. 864,671.

To all whom it may concern:

Be it known that I, WILLIAM ZURICH, a subject of the Queen of the Netherlands, having declared my intention of becoming 5 a citizen of the United States, residing at Princeton, in the county of Mercer and State of New Jersey, have invented new and useful Improvements in Framing-Tools, of which the following is a specification.

10 The invention relates to a framing tool, and more particularly to the class of protractors.

The primary object of the invention is the provision of a device of this character 15 wherein the user can determine with accuracy the true line of cut of hip or valley rafters, jack rafters or the like, and the length thereof, in accordance with the run or width of a building, the faces of the protractor or device being marked with scales 20 and lines indicative of different pitches with tabulations to enable the framing of the rafters with accuracy correspondingly with respect to the run or width of a building 25 under construction.

Another object of the invention is the provision of a protractor or device of this character wherein the scales, lines and tabulations are arranged in a novel manner to enable 30 a user to reckon with accuracy the framing of rafters without necessitating mental calculation for the true framing of the rafters for the construction of a building.

35 A further object of the invention is the provision of a protractor or device of this character which is simple in construction, reliable and handy in use, and inexpensive in manufacture.

40 With these and other objects in view, the invention consists in the construction, combination and arrangement of parts as will be hereinafter fully described, illustrated in the accompanying drawing, and pointed out 45 in the claim hereunto appended.

In the drawing:—Figure 1 is a plan view of a protractor constructed in accordance with the invention, looking toward one face thereof. Fig. 2 is a similar view, looking 50 toward the opposite face. Fig. 3 is an edge elevation.

Similar reference characters indicate corresponding parts throughout the several views in the drawing.

55 Referring to the drawing in detail, the protractor or device comprises a rectangular

shaped plate 5, preferably made from metal, one face thereof being marked to indicate the outlines of reversely arranged squares A and B, respectively, the arms 6 thereof being parallel with each other, while the arms 7 are likewise parallel with each other. Arranged between the arms of the squares A and B centrally of the plate are series of longitudinal and transverse lines arranged 65 in spaced parallel relation to each other in each series to form therebetween rows of spaces 8 in which are located numerals and fractions thereof indicative of a table of measurement, while at one end of all of the 70 rows of spaces 8 is a caption "Diff. J. R.", which designates "different jack rafters", while the areas of the squares A and B are marked with angularly disposed lines 9, and a scale of fractions therebetween, so that 75 these lines will enable the accurate determination of different pitches of rafters when the same are to be cut for the framing thereof in the construction of a building. At the ends of each square are the captions 80 "S. C. H. & V. R."; "P. C. H. & V. R."; "S. C. J. R.", and "P. C. C. R.", which are the capital letters of the names of the various rafters and cuts used in framing a building, or edifice, such as side cuts, common, hip, valley and jack rafters, as well as the pitch thereof for the lining of the same to enable the accurate cutting thereof prior 85 to the framing of such rafters. At the margin of the squares A and B throughout 90 the length of the arms thereof are numerals and fractions thereof which coöperate with the lines 9 to enable the user of the device to determine the length of such rafters, while the edges of the plate 5 will 95 give the proper cut according to the pitch thereof. The plate 5 on the other face thereof is marked with lines to form tabulation spaces indicative of independent tables 10 and 11, respectively, the spaces thereof being supplied with numerals and fractions representing scales for determining 100 the lengths of common rafters, or hip and valley rafters. The table 10 is headed with a caption "Length C. R", while the table 11 is headed with the caption "Length H. & V. R.".

Located above the caption of the table 10 is a row of transverse spaces 12, while in the left-hand space of this row is the 110 word "Run", while in the remaining spaces of the said row are numerals ranging from

2 to 12 consecutively, the spaces containing the numerals being in alinement with the spaces of the tables 10 and 11, thereby enabling the user of the device to determine 5 the lengths of the common and hip or valley rafters. By the use of the face of the plate 5 containing the tables 10 and 11 and the spaces 12 the user can determine the lengths of common and hip or valley rafters, in correspondence to the different runs, pitches 10 and the rises thereof. Now, in the use of the device, by reference to the other side of the plate 5, containing the squares A and B, pitch lines and scales, the lengths of 15 jack rafters, plumbs and side cuts, as well as the same with the common rafters or valley rafters can be taken with accuracy.

It will be apparent that the tables 10 and 11 show scales for determining the different 20 lengths of common, hip and valley rafters, while the table 10 is headed with a row of numbers ranging from 2 to 12 consecutively, which are indicative of the different runs of one-half of the width of a building to 25 be constructed.

In the use of the protractor for the framing of a roof, assuming that it is desired to lay out a common rafter for a roof one-eighth or three inches to a foot pitch for a 30 building twenty-four feet wide which has a ten foot run, it is necessary for the user of the protractor to locate the one-eighth or three inch scale to a foot run at the left hand side of the common rafter table 10 35 and after doing this the scale in this row containing the one-eighth or three inch foot run is followed toward the right hand side of the table 10 until the numeral 12 above said row is observed, and in this row at this 40 point will indicate the length of the common rafter. Should the roof be over a twelve foot run, for example, sixteen feet one-eighth pitch, to obtain the length of the common rafter the user of the protractor 45 observes the twelve foot run which will indicate at the right hand side of the table 10 twelve feet four inches, and also observation is made of the four foot run which, in the first row of the table 10, indicates four feet, 50 one and three-eighths, and these two are added together, which will give sixteen feet and three-eighths, which is the length of the common rafter. For a one foot run it is necessary to use the twelve foot run on the 55 table 10 and in this event the user reckons by inches instead of by feet. For example, a one-eighth pitch roof, twelve feet six inches run in this table, it will be observed

with a run 12 there will be found twelve feet, four inches, and under run six will be 60 reckoned six and two-twelfths inches and not six feet, two inches, because it is a six inch run instead of a six foot run. For example, a twelve foot, four inch run plus six and two-twelfths inches would equal twelve 65 feet, ten and two-twelfths inches which is the length of the rafter.

In determining the length of hip and valley rafters the table 11 is employed and the same reckoned correspondingly to the 70 measurements of the common rafters. To obtain lengths of jack rafters the table or scale on the reverse side of the protractor is used. The first row of figures on the top will give the different spaces of jack and 75 cripple rafters, while the figures on the left hand side will give the different pitches, it being necessary to follow the figures on the given pitch toward the right hand side until the given pitch space has been reached 80 where it will indicate how much shorter to cut each rafter.

To frame a jack rafter for a roof one-eighth pitch space twenty inches at center, 85 find one-eighth pitch on left hand side of the jack rafter table, follow the row of figures to the right hand side until the numeral 20 has been reached at the top of this table and in the vertical row there will be found one foot, eight and one-half inches 90 which is the difference in length of jack rafter.

From the foregoing it is thought that the construction and manner of use of the device will be clearly understood, and therefore a 95 more extended explanation has been omitted.

What is claimed is:—

A framing tool comprising a rectangular shaped plate having one face laid off to form 100 reversely disposed squares, the arms of which are parallel with each other, a table or scale columns disposed between a pair of the parallel arms of the plate and having scale indicia indicative of the difference in 105 the length of jack rafters, said squares having markers within the areas thereof indicative of pitches of side cuts, plumbs, and common, hip, valley and jack rafters.

In testimony whereof I affix my signature 110 in presence of two witnesses.

WILLIAM ZURICH.
